UNITED STATES PATENT OFFICE.

WILLIAM S. WITTEN, OF CHICAGO, ILLINOIS.

LATCH.

Application filed March 3, 1922. Serial No. 540,688.

To all whom it may concern:

Be it known that I, WILLIAM S. WITTEN, a citizen of the United States, and a resident of Chicago, in the county of Cook and State 5 of Illinois, have invented certain new and useful Improvements in Latches, of which the following is a specification, reference being had to the accompanying drawings.

My invention relates primarily to latches 10 or locks of the type in which the latching or locking bolt moves to its operative position by gravity, as distinguished from those in which it is moved to such position by a spring, although certain features thereof 15 may be incorporated in spring actuated latches. It has for its object to provide an improved latch together with a keeper therefor, in which the bolt will operatively and securely engage the keeper upon the 20 closing of the door or gate to which the latch is attached even if for any reason, such as the incomplete closing of the door, or inaccurate mounting of the latch or keeper, the bolt engages the keeper only to 25 a limited extent. I accomplish this object as illustrated in the drawings and herein-after described. What I regard as new is set forth in the claims.

In the accompanying drawings,—

Fig. 1 is a side elevation of my improved latch with one of the side plates of the case removed, showing also the keeper in section;

Fig. 2 is a view of part of the side of a barn or other outhouse showing my improved latch and keeper applied to the door thereof;

Fig. 3 is an enlarged detail, being a partial vertical section on line 3—3 of Fig. 1;

Fig. 4 is an enlarged detail, being a partial vertical section on line 4—4 of Fig. 1 showing the locking device for locking the latch in operative position;

Fig. 5 is a view showing a modified construction designed for use in connection 45 with a swinging door, said view being a section on line 5—5 of Fig. 6;

Fig. 6 is a horizontal section on line 6—6 of Fig. 5;

Fig. 7 is a view showing my improved 50 latch applied to a vertically sliding door;

Fig. 8 is another modification showing my improved latch and keeper adapted for use on a freight car door;

Fig. 9 is a side view of part of a freight 55 car showing the manner in which the latch shown in Fig. 8 may be applied thereto;

Fig. 10 is a section on line 10—10 of Fig. 8; and

Fig. 11 is a detail, being a cross-section on line 11—11 of Fig. 8.

Referring first to the construction shown in Figs. 1 to 4, inclusive,—12 indicates the latch as a whole, said latch comprising a stem or shank 13 mounted at its upper end on a pivot 14 and having at its lower end 65 a curved latch bolt 15 projecting at one side of the stem 13, and a counterbalancing arm 16 which projects at the opposite side of the stem, thus giving the latch as a whole somewhat the appearance of an inverted T. 70 At the upper end of the stem 13 is an operating arm or handle 17 rigidly connected with the stem 13 and extending at an angle with said stem over the arm 16. The balance of the latch is such as to tend to swing 75 the latch in a clockwise direction as viewed in Fig. 1 so that the latch bolt 15 is projected and normally assumes that position. The latch is mounted in a suitable case comprising a side plate 18 having a flange 19 80 along its lower margin forming the bottom of the case; a flange 20 at its outer edge between the pivotal portion of the latch and the latch bolt 15 forming a stop which limits the extent to which the latch bolt 85 may project; and a flange 21 at the opposite side of the case which serves as a spacing block and also to limit the inward movement of the latch. A cover plate 22 fits upon the flanges 19, 20 and 21 and forms 90 a closure for that side of the case, said cover plate being preferably fitted on dowel pins 23 provided at suitable points to position the cover plate. 24 indicates screws for securing the case to the door or other 95 structure to which it is applied. 25 indicates an arcuate slot in the side plate 18 adjacent to the stem 13 through which projects a pin 26 connected with the stem, as shown in Fig. 3. The door 27 or other part 100 to which the latch is applied is provided with an arcuate slot 28 similar to and registering with the slot 25, and the pin 26 extends through the slot 28 so that when the latch is applied to the door it may be moved out of operative position by means of the pin 26, notwithstanding the fact that the arm 17 is at the opposite side of the door.

As will be readily understood from an inspection of Fig. 1, the latch normally occupies the position shown in full lines in said

figure, but is capable of being swung to the position shown in dotted lines by means either of the arm 17 or of the pin 26, and that when so moved the counterbalancing arm 16 swings back under the lower margin of the flange 21. As soon as the operating arm is released the latch bolt 15 will turn to the position shown in full lines in said figure under the action of gravity. For locking the latch bolt in its projected position I provide a dog 29 which is mounted on a pivot 30 fitted between the side members of the case at a point adjacent to the inner end of the counterbalancing arm 16, said dog being so arranged that it may be swung into or out of position back of said arm, either by a key arranged to engage one of the ends of the pivot 30, which are made non-circular in contour for that purpose as shown in Figs. 1 and 4, or by means of a finger piece 31 carried by the dog 29 and projecting out beyond the members of the case as shown in Fig. 1. The dog 29 is also provided with laterally-extending lugs 32 which are arranged to overlap the side members of the case to limit the extent to which the dog may be swung down behind the counterbalancing arm 16. By this construction, when the dog 29 is in the position shown in Fig. 1 it lies in the path of the counterbalancing arm 16 and prevents the latch from being swung out of operative position, but by swinging said dog in a clockwise direction as viewed in Fig. 1 it may be moved out of the way to permit the latch to be moved to its inoperative position. If then it be desired to secure the latch in the latter position the dog may be swung back to its operative position when it will underlie the inner end of the counterbalancing arm 16, as shown by dotted lines in Fig. 1, and thereby will operate to prevent the latch from swinging back into locking position.

In the construction shown in Fig. 1, the keeper comprises a block 33 which is preferably substantially semi-cylindrical since it is provided with two convex oppositely-disposed curved surfaces 34, 35 extending to a plane surface 36, the latter being the outer surface of the keeper when it is mounted in position. It will be understood, however, that the two curved surfaces 34, 35 are provided to make the keeper reversible, and that only one of such surfaces or its equivalent is essential. These curved surfaces of the keeper preferably conform in curvature to the concave or operative surface of the latch bolt 15, which in the arrangement shown in Fig. 1 is its upper edge, and the keeper is so disposed with reference to the bolt and the pivot of the latch that the bolt will always operatively bear against the keeper along a line radial to the pivot of the latch, or substantially so. It will be apparent therefore that so long as any part of the

latch bolt engages any part of the keeper the door will be securely latched, because if it be attempted to open the door, the line of direction of the force applied through the bolt to the keeper will approximately intersect the pivot 14 and consequently the bolt will not tend to swing out of operative position. This feature is of great importance because it frequently happens that the door is closed carelessly so that a complete closure is not effected, or sometimes through an accumulation of snow, dirt, &c., the door cannot be completely closed, or the latch or keeper may not have been mounted exactly in the proper position. Nevertheless, my improved latch will operate to effectively secure the door even though a very small portion of the latch bolt engages the keeper. Moreover, any shaking of the door by the wind or other causes will not tend to release the latch, but on the contrary will tend to cause the latch bolt to project further since gravity has a constant tendency to project it to the limit of its movement in that direction. The keeper is preferably fitted between suitable side plates 37 and is wholly or partially enclosed by a flange 38, as shown in Fig. 1. It may either be secured to the jamb 39 of a door as shown in Fig. 2, or it may be fitted in a recess in the door jamb as shown in Figs. 5 and 6.

In Fig. 2 I have illustrated my improved latch as mounted on a sliding barn door 27, in which case it is secured to the front marginal portion of the door at any suitable height.

The construction shown in Figs. 1 to 4 is adapted for use in connection with any ordinary horizontally sliding door, and it may also be used in connection with a vertically sliding door as shown in Fig. 7, in which case the latch is preferably secured adjacent to the upper plate 40 of the door opening and the keeper, indicated as a whole by reference numeral 41, is secured to the lower portion of the door 42. In this arrangement the latch is turned to a position at right angles to that shown in Fig. 1 so that the latch bolt 15 projects downward. Consequently, when the door is raised the keeper will be engaged by the latch bolt, which will operate to hold the door in its elevated position.

In Figs. 5 and 6 I have shown my improved construction applied to a horizontally-swinging door 43 hinged at 44. In this arrangement the keeper is set into a recess 45 formed in the door jamb 46 so that its plane face 36 is parallel with the inner surface of the door when the latter is closed. The latch is secured to the outer edge of the door in such position that when the door is closed the latch bolt 15 will be adapted to engage the keeper, as shown in Figs. 5 and 6. The construction shown in these fig-

ures is substantially the same as that shown in Figs. 1 to 4, except that preferably instead of the operating arm 17 arranged as shown in Fig. 1 I provide an operating arm 5 47 which is connected with the lower portion of the latch and extends outward at an angle thereto so that it may conveniently be operated when the door is closed. This handle may, if desired, be provided with an enlarged head 48 to increase its counter-balancing action.

In Figs. 8 to 11, inclusive, I have shown my improvements applied to a latch adapted for freight car doors. In the latter figures 15 49 indicates a freight car and 50 the usual sliding door thereof adapted to slide longitudinally of the car and also to be swung outwardly away from the side of the car, its lower margin being free to swing in that 20 direction when unlocked. The general construction of the latch shown in these figures forms the subject-matter of a separate application filed by me of even date herewith, and the purpose of these illustrations therefore 25 is merely to show the manner in which my improved latch bolt and keeper may be incorporated in a latch for use in freight car doors. In the construction shown in these figures the stem portion 51 of the latch 30 is curved, but the latch bolt 52 is the same as that shown in the preceding figures except that it is rounded at the sides, as shown in Fig. 11, to cooperate with an inclined guide plate 53 provided at one side of the 35 keeper 54 so that when the door is swung inwardly or toward the side of the car the latch bolt 52 will ride up on said guide plate and drop behind the keeper block 55, as best shown in Figs. 8 and 10, thereby assuming 40 its operative relation thereto. When the door is slid to its closed position without being swung outwardly the curved outer surface of the locking bolt 52 will ride up on the outer surface of the keeper block 55 45 until it passes back of said block, whereupon the locking bolt will drop into its operative position.

As clearly shown in Fig. 8, in this arrangement the locking bolt 52 extends downward, 50 the latch being mounted upon a pivot 56 in the lower portion of the case 57. The latch is released by means of an operating arm 58 connected with the pivotal portion of the stem 51, and may be locked in operative 55 position or be held out of operative position by means of a locking arm 59 provided for that purpose, as more fully explained in the copending application hereinbefore referred to. It is not believed to be necessary 60 to describe the construction shown in these figures more in detail at this time inasmuch as they do not relate to the subject-matter of this application.

In the construction shown in all the figures as the door moves to its closed position

the outer end portion of the latch bolt strikes the plane face 36 of the keeper and consequently the latch swings back out of operative position, but as soon as the backward swinging of the latch brings it into position 70 to pass the outer edge of the said face the latch bolt swings back again into engagement with the operating face of the keeper and the latch becomes effective to hold the door closed regardless of the extent to which 75 the operative surfaces overlap, as above pointed out. So far as I am aware I am the first in the art to provide a latch and keeper cooperating in this manner, and my invention, therefore, includes such construction generically. Furthermore, my invention is not limited to a latch bolt and keeper of the specific shape illustrated as such shape may be modified considerably without departing from my invention. It will 80 be understood also that while the latch is usually applied to the door and the keeper to the door jamb or other suitable support, the arrangement may be reversed.

What I claim as my invention and desire 85 to secure by Letters Patent, is—

1. The combination with a pivotally mounted latch comprising a shank and a hook-shaped bolt projecting laterally therefrom, of a keeper arranged to be contacted by the outer end portion of the bolt to turn the latch and thereafter be operatively engaged by said bolt along a line substantially radial to the pivot of the latch.

2. The combination with a pivotally mounted latch comprising a shank and a hook-shaped bolt projecting laterally therefrom, of a keeper arranged to be contacted by the outer end portion of the bolt to turn the latch and thereafter be operatively engaged by said bolt along a line substantially radial to the pivot of the latch, said bolt being normally held in operative position by gravity.

3. The combination with a hook-shaped latch comprising a pivotally mounted shank and a latch bolt extending at an acute angle from the shank at a point remote from the pivot thereof, of a keeper adapted to be contacted by the outer end portion of the bolt to turn the latch and thereafter be operatively engaged by the inner marginal portion of said latch bolt.

4. The combination with a hook-shaped latch comprising a pivotally mounted shank and a latch bolt extending at an acute angle from the shank at a point remote from the pivot thereof, said latch bolt being normally held in operative position by gravity, of a keeper adapted to be contacted by the outer end portion of the bolt to turn the latch and thereafter be operatively engaged by the inner marginal portion of said latch bolt.

5. The combination with a pivotally

1 mounted latch comprising a shank and a laterally-projecting bolt provided with a concave engaging surface, of a keeper comprising a member having a convex surface 5 adapted to be engaged by the concave surface of the bolt when the latter is projected, said keeper being adapted to be contacted by the outer end portion of the bolt to turn the latch into position to enable it to make 10 such operative engagement with the keeper.

6. The combination with a pivotally mounted latch comprising a shank and a laterally-projecting bolt provided with a concave engaging surface, of a keeper comprising a member having a convex surface 15 adapted to be engaged by the concave surface of the bolt when the latter is projected, said bolt being normally projected by gravity, and said keeper being adapted to be 20 contacted by the outer end portion of the bolt to turn the latch into position to enable it to make such operative engagement with the keeper.

7. The combination with a sliding door, 25 and a latch comprising a pivotally mounted shank having a hook-shaped bolt projecting laterally therefrom, of a keeper arranged to be contacted by the outer end portion of the bolt to turn the latch and thereafter be 30 operatively engaged by said bolt along a line substantially radial to the pivot of the latch.

8. The combination with a sliding door,

and a latch comprising a pivotally mounted shank having a hook-shaped bolt projecting laterally therefrom, of a keeper arranged to be contacted by the outer end portion of the bolt to turn the latch and thereafter be 35 operatively engaged by said bolt along a line substantially radial to the pivot of the latch, said bolt being normally projected by gravity.

9. The combination with a door arranged to slide endwise and also to swing laterally, and a latch comprising a pivotally mounted shank having a hook-shaped bolt, of a keeper operating to move said bolt out of operative position when the door is being moved inward or endwise to its closed position, and to permit the bolt to move into engagement with the keeper when the door is closed, said keeper being arranged to be 45 operatively engaged by said bolt along a line substantially radial to the pivot of the latch.

10. The combination with a pivotally mounted latch comprising a shank and a hook-shaped bolt projecting laterally therefrom, of a keeper arranged to be contacted by the outer end portion of the bolt to turn the latch and thereafter be 50 operatively engaged by said bolt along a line substantially radial to the pivot of the latch, and means for locking said bolt in its operative position.

WILLIAM S. WITTEEN.
